UNITED STATES PATENT OFFICE

1,938,467

CIRCUIT BREAKER

William Russell, Hartshorne, Okla.

Application June 17, 1932. Serial No. 617,904

1 Claim. (Cl. 200—106)

This invention relates to electro-magnetically operated circuit breakers or switches of the single pole type and the object of the invention is to provide a circuit breaker which is operated by an electro-magnet when an overload or other abnormal conditions occur on the line and to further provide a device which is simple and durable in construction yet very positive in action, being more sensitive than fuse plugs which are normally used to protect circuits, all as will hereinafter be more fully described and claimed.

Referring to the accompanying drawing, which is made a part hereof and on which similar reference characters indicate similar parts.

Figure 1 is a front view in elevation of the device in closed position, and

Figure 2, a section on line 2—2 of Figure 1.

In the drawing reference character 10 indicates the base of the switch formed of any suitable insulating material having contact posts 11 and 12 secured by any suitable means thereto. The posts are provided with terminals 13 and 14. A curved blade 15 is pivoted near its center to the post 12, one end of which engages the post 11 when in closed position to complete the circuit between the posts. The post 11 is provided with a stop 40 which prevents the blade 15 from being depressed too far and yet allows the parts of the post 11 to spring apart. The other end is pivotally connected to a rod 16 slidably mounted through the opening 17 in the casing 18 which is secured to the base 10 by any suitable means 19. A disk 20 is secured to the inner end of the rod and a spring 21 is positioned around the rod between the disk and the end of the casing normally holding the other end of the blade 15 out of contact with the post 11 as shown in the dotted line position in Figure 2. A handle 22 is fixed to the blade 15 for use in closing the switch. The blade 15 is provided with an inwardly projecting hook portion 23 which engages the short end 24 of the arm 25 pivotally mounted at its center on a shaft 26 which is positioned at the center of the base 10. The arm is provided with a sleeve 27 around the shaft and is retained on the shaft by means of a pin 28 through the shaft and is also provided with a narrow plate 39 on the underside to prevent undue wear when being engaged by the hook 23. The arm 25 is formed of a suitable insulating material and is provided with a counter-weight 29 secured on the long end 30 by the bolts 31. The counter-weight is formed of laminated metal suitable to be acted upon by a magnetic force and serves as an armature.

A magnet 32 is mounted on the base in any suitable manner above the counter-weight and is likewise formed of laminated material. One arm 33 of the magnet 32 is provided with a winding 34 suitably insulated and of suitable characteristics connected at one end 35 to the post 13 and at the other end 36 to the post 37 on the base 10. A stop 38 is provided on the base below the counterweight to prevent the end 24 from rising to such a point where it would not be engaged by the hook 23 to hold the switch in closed position.

Suitable openings 41 are provided for mounting the switch in position.

The operation of the device is as follows:

The switch is mounted as shown in Figure 1 and is connected in one line of a circuit at the terminals 14 and 37. The arm 25 occupies the position shown in Figure 1 due to the position of the counter-weight or armature 29. The blade 15 is held out of contact with the post 11 by the spring 21. To close the switch, the handle is depressed and the hook portion 23 rides over and engages the arm 25 which holds it in closed position. The magnet is of such a construction as to be energized by the normal load but of a strength insufficient to attract the armature. Upon the development of any overload or any other abnormal conditions in the circuit the magnet will be energized to such an extent as to attract the armature and thus break the circuit, the parts resuming the open position as first described.

From the above described device it is clearly seen that a circuit in which the device is connected is protected in a positive manner and by a device which is highly sensitive to any abnormal condition which may occur. The device is simple in construction, cheap in manufacture and perfect in operation for the purpose for which it is intended to be used.

It will be obvious to those skilled in the art that various changes may be made in my device without departing from the spirit of the invention and therefore I do not limit myself to what is shown in the drawing and described in the specification, but only as indicated by the appended claim.

Having thus fully described my said invention, what I claim as new and desire to secure by Letters Patent, is:

A circuit breaker comprising a base, a contact positioned on said base, a blade movable in a plane at right angle to the base pivoted intermediate its ends to said base with one end there-

of adapted to engage said contact, means positioned between the other end of said blade and said base biased to hold said blade in open position, an arm parallel to said base and pivoted intermediate its ends having an armature secured to one end for raising the other end of said arm, means for limiting the downward travel of said armature, means on said blade adapted to

engage said arm when said blade is pushed inwardly and an electro-magnet positioned above said armature adapted to attract said armature upon overload of said circuit thereby releasing said blade to break the circuit, substantially as set forth.

WILLIAM RUSSELL.
